(57) **CLAIM**

The ornamental design for a container lid, as shown and described.

DESCRIPTION

FIG. 1 is a left, front, top perspective view of a container lid showing my new design;

FIG. 2 is a right, rear, bottom perspective view thereof;

FIG. 3 is a right, rear, top perspective view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top plan view thereof;

FIG. 9 is a bottom plan view thereof; and,

FIG. 10 is a left, front, top perspective view of the container lid of FIG. 1, in which an outlet lid is in an open position. In the drawings, the evenly broken lines represent parts of the article that form no part of the claim. The dot-dash broken lines represent the boundaries of the claim and form no part thereof.

1 Claim, 10 Drawing Sheets

Related U.S. Application Data

continuation of application No. 18/014,147, filed on Dec. 31, 2022.
